5 Claims. (Cl. 128—528)

This invention relates to a girdle and more particularly to a panty girdle.

The invention has for an object the provision of a girdle with a window having a diamond or similar shape on the front and abdominal part of the girdle which consists of flexible net cloth, said window being fitted with a front piece having four sides each of which is shorter in length than each side of the window, both the girdle and the front piece being made of the same material, preferably elastic, and these being sewn together to obtain a complete girdle.

The above and further objects and advantages of this invention will be apparent from the following description of the invention as illustrated in the accompanying drawings, in which:

FIG. 1 is a front view of a pattern for said panty girdle before the window and the front piece are sewn together;

FIG. 2 is a plan view of the panty girdle in which the window and the front piece have been sewn together; and

FIG. 3 is a plan view of the panty girdle on a wearer.

There is proposed in accordance with the invention the provision of a window C having a diamond or similar shape, with curved sides, cut into the abdominal region of a girdle B of flexible net cloth such as known by the tradename Operon Power Net or stretchable cloth and fitted with a front piece A consisting of the same cloth as the girdle. Each side 1, 2, 3, and 4 of the front piece is shorter than each corresponding side 5, 6, 7, and 8 of the window and the sides of the front piece A are stretched and sewn to the corresponding sides of the window. That is, the front piece A is such that the area that covers the window C is smaller than the open area of the window prior to sewing. Also, as seen from FIG. 1, the relation between the window C and the front piece A is such that the difference between the lateral dimensions of the window and the front piece is greater than the difference between the longitudinal dimensions of the window and the front piece. This results in imparting a greater lateral stretching force to the front piece and its vicinity. In sewing the front piece to the girdle body, preferably the sides of the front piece are stretched although the sides of the window can be gathered instead.

Due to the fitting of the front piece to the window, there are found a number of wrinkles or folds in waveform along the edges of the window but the wrinkles are smoothed out by the stretching of the cloth of the girdle when the latter is put on by a wearer, while the stretching of the front piece particularly compresses the abdomen thus sewing to reshape the same and thus improving the figure of the wearer.

In order to reshape the abdomen, the conventional girdles have hitherto used unstretchable cloth for the front part of diamond shape or layers of Power Net cloth to limit the stretching of cloth possibly on the front part and thus to compress the abdomen indirectly by the pulling force of the Power Net encircling the body. With respect to the layer construction of the unstretchable or Power Net cloth, the compression was effected mainly from the expansion or contraction of the girdle around the body. However, in such construction, the front piece itself did not compress the abdomen effectively or positively, but just supported it passively so that for firmly

2

holding the abdomen a rather strong tension was employed for giving a great compression on the whole body.

Further, if it is required to give flexibility and thereby large dimensions of the girdle for the waist, it is almost impossible to reshape the abdomen, although this is the essential object of the girdle.

As hereinbefore described, it is evident that if an unstretchable diamond front is used the body will lose freedom of movement and consequently the continued wearing of the girdle may prove quite unhealthy for the body.

With this in view, the present invention provides a unique and ideal type of the girdle which enables compressing the abdomen exclusively while having no influence on the other parts of the body. The girdle made of Operon Power Net cloth is stretchable in both lateral and vertical directions and when a wearer puts it on, the front piece will stretch about 69% more in the lateral direction than about 70% more in the vertical direction. It should be noted specifically that a stronger stretching force is exerted on the front part of the girdle.

Another advantage of the invention is its excellent adaptability to movement of the body thereby enabling it to keep all the daily postures of the body as ideal as possible. It will be understood that the girdle of this invention is adapted quite well to the body in case of bending. Besides it is very important that the girdle is well fitted to remove the compression from the abdomen in a sitting posture. In contrast to the conventional girdle whose compression is rather weak on the body in a standing posture but too strong for the same in a sitting condition, the girdle of this invention is able to act more effectively on the abdomen of the wearer in a standing posture and it can readily adjust to the abdomen in a sitting posture.

The aforesaid features of the girdle are still further amplified by use of a Power Net cloth made of 280 deniers Operon yarn which is weaker than ordinary Operon 420 deniers yarn. The Power Net cloth of 280 deniers yarn is weaker in respect of stretching force so that it cannot serve to reform the figure of the abdomen when applied in conventional girdles. However, the girdle according to this invention is not affected by the weakness of the Power Net cloth in stretching. Since it is the aim of the girdle to lessen the compression of the body, it is much better for the cloth to be weak. As the stretching force of the front part is formed by the balance of power of construction, the girdle can work most effectively not being affected by the quality of material yarn. Thus, with good adaptability to movement of the body, removal of compression, and light weight, the girdle of this invention can fulfil the important requirements of foundation garments. The simple construction and fine material avoids unnecessary thickness by virtue of its thinness and strength.

55 What is claimed is:

1. An article of apparel comprising a girdle body provided with a window of generally diamond shape at the front region of said girdle body, and a front piece of said shape connected to corresponding sides of body at said window, said girdle body and said front piece both consisting of a material stretchable in lengthwise and widthwise directions, and the area of said front piece covering said window being smaller than that of said window before being connected to said girdle body, said front piece being connected to said girdle body with each side of said front piece being in stretched condition.

2. An article of apparel according to claim 1 wherein the lateral and longitudinal dimensions of said window and front piece are different and the difference between the lateral dimensions of said window and said front piece is greater than the difference between the

longitudinal dimensions of said window and said front piece so that a greater lateral stretching force is imparted to said front piece and to the body adjacent said front piece.

3. An article of apparel according to claim 1 wherein said girdle body and said front piece are of the same material.

4. A method of making a girdle comprising cutting a girdle pattern of two-way stretch material and forming in the same a generally diamond shaped window at a position corresponding to the front of the girdle cutting a generally diamond shaped front piece of two-way stretch material with an area smaller than that of said window, stretching the front piece and sewing the stretched front piece to the pattern.

5. A method as claimed in claim 4 comprising cutting the window and front pieces with different lateral and longitudinal dimensions and with the difference between the lateral dimensions being greater than the difference between the longitudinal dimensions, the front piece being stretched more laterally than longitudinally.
